Primary Examiner—Cathy Anne MacCormac

[57] CLAIM

The ornamental design for the bird cage, as shown and described.

DESCRIPTION

FIG. 1 is a right elevational view of the bird cage showing my new design;

FIG. 2 is a rear elevational view thereof;

FIG. 3 is a front side elevational view thereof;

FIG. 4 is a top plan view thereof;

FIG. 5 is a bottom plan view thereof; and,

FIG. 6 is a top and right side perspective view thereof, the broken line showing of the tree is for illustrative purposes only and forms no part of the claimed design.
